Dec. 722

Russel Wheeler, & Stephen A. Bailey, of Utica N.Y.
Letters Patent No. 722. Dated August 24th 1855

The schedule referred to in these Letters Patent, and making part of the same.

To all whom it may concern:

Be it known, that we Russel Wheeler, and Stephen A. Bailey of the City of Utica in the County of Oneida, and State of New York, have invented, or produced a new and original design for the exterior configuration and ornament of a Coal Burning Stove, denominated by us the "Belle of Utica"

The aforesaid ornaments are in alto. relief, and are shown by the annexed drawings, which form a part of this specification.

Fig. 1 is an exterior elevation of the stove, showing the configuration of the front and one of its sides. The opposite side not here shown, is similar to that seen, having similar oven doors, and is ornamented in the same manner. The rear end not seen in the drawing, is unlike the front, having no doors and is ornamented by three strips of ornaments like those seen at the front corner from R to X, standing vertically as here seen, and parallel to each other.

The sides of the stove are alike in their construction, and are similarly ornamented. The doors both in front and at the sides are similarly ornamented, each having a large diamond figure standing

within a parallelogram. The latter being also surrounded by a light border of diamond shaped figures. The interior of the above and large diamond, as well as the exterior corners, within the parallelogram, being filled up with figures, resembling a variety of crystalline planes, as is shown upon the doors in the figure.

The surface of the top plate, for convenience in use, is without ornaments, and has in the usual form four brazier holes as is seen, together with the funnel T, for the smoke pipe. This plate however, has a heavy ornamental moulding U projecting from its outer edge all round.

The mouldings used upon this stove are of four principal patterns.

First - the moulding u, which encircles the top plate. This is shown on a scale equal to the full size in Fig. 2, a being a face view and b a section.

Second. The moulding S, (fig 1) cast upon the bottom plate all round except the opening left in the front for the hearth plate. This breach ..... however is supplied by a similar moulding on the damper or valve V, which when closed completes the circuit of this moulding. This moulding is also shown enlarged to full size in fig 3. a being a face view of it, and b a section.

Third. The moulding F. (Fig. 1) surrounding the hearth, and differing somewhat in its figure from the moulding S just mentioned. This is enlarged in fig 4. a being a face view and b a section.

Fourth. The small moulding shown of the full size at a. b. (fig 5) and appears on the stove at C, and d, on each side of the mould hearth

The diamond shaped ornaments shown in Figs 6. & 7. form a line at the base and at the top of the several upright plates, these figures alternating with each other, and forming when the plates are set up, a line quite round the stove, at bottom and top, as shown at f. and h. (fig 1.) These also are in alto relief, as are all the ornaments here described. These same ornaments (fig 6. & 7.) occupy in a vertical position, the four corners of the stove, alternating in the same manner as before as shown at i. & k. An ornament resembling the center of the diamond before described as occupying the center of each of the doors is cast on the knee of each of the stove legs, being curved in a bent form over the knee as seen at m. & n. and a single star is cast upon the upper side of all the feet as shown at o: all the legs and feet being ornamented the same.

The words "Belle of Utica" in Roman Capital, appear on a smooth ground immediately over the front doors, as seen at P. And the words "Wheeler & Bailey" in like characters appear on the face of the hearth, as shown at t.

We claim as new and desire to secure by Letters Patent
the configuration of surface, and combination of ornaments constituting the exterior design of
